UNITED STATES PATENT OFFICE

116,861

DESIGN FOR A MILK BOTTLE

George N. Mas, Lynchburg, Va.

Application April 19, 1939, Serial No. 84,392

Term of patent 14 years

To all whom it may concern:

Be it known that I, George N. Mas, a citizen of the United States and residing at Lynchburg, Virginia, have invented a new, original, and ornamental Design for a Milk Bottle, of which the following is a specification, reference being had to the accompanying drawing, forming part thereof.

Fig. 1 is a side elevational view of the milk bottle showing my new design.

Fig. 2 is a transverse sectional view on line 2—2 of Fig. 1 looking in the direction of the arrows, and

Fig. 3 is a bottom plan view.

The bottle has substantially the same appearance when viewed from any side.

What I claim is:

The ornamental design for a milk bottle, as shown and described.

GEORGE N. MAS.
